DESIGN FOR A HEAD FOR A PORTABLE
SEWING MACHINE

Sidney R. Bell, Stamford, Conn., assignor, by
direct and mesne assignments, to Irving J.
Moritt, Brooklyn, N. Y.

Application May 25, 1948, Serial No. 146,569

Term of patent 14 years

(Cl. D70—1)

To all whom it may concern:

Be it known that I, Sidney R. Bell, a citizen of the United States and residing in Stamford, county of Fairfield, and State of Connecticut, have invented a new, original, and ornamental Design for a Head for a Portable Sewing Machine, of which the following is a specification, reference being had to the accompanying drawing, forming a part thereof, in which:

Fig. 1 is a perspective view of a head for a portable sewing machine, showing my new design;

Fig. 2 is a plan view thereof;

Fig. 3 is a front elevation thereof;

Fig. 4 is an elevation, showing the needle end of the head; and

Fig. 5 is an elevation, showing the opposite end of the head.

I claim:

The ornamental design for a head for a portable sewing machine, substantially as shown.

SIDNEY R. BELL.
